WRAPPER SUITABLE FOR MENSTRUAL PADS

Filed Sept. 27, 1946

UNITED STATES PATENT OFFICE

2,506,238

WRAPPER SUITABLE FOR MENSTRUAL PADS

Richard Everard Shewan Rowe, Johannesburg,
Transvaal, Union of South AfricaApplication September 27, 1946, Serial No. 699,901
In the Union of South Africa November 22, 1940

6 Claims. (Cl. 128—290)

1

This invention relates to wrappers suitable for use as a bandage or as a holder for pads such as menstrual pads; and also relates to menstrual pads.

When a bandage is applied to a surface of a thigh which faces the similar surface of the other thigh, such bandage is liable to bring about chafing of the other thigh, particularly when the bandage gets wet and when it is permeated by blood which coagulates on the outside of the bandage and forms a rough surface. The same drawback is frequently encountered in connection with menstrual pads which often cause chafing.

An object of this invention is the provision of a wrapper of the kind above described which minimises or prevents chafing. Another object of this invention is the provision of such wrapper which can be produced cheaply enough to permit of its being discarded after a single use; and which can be disposed of in the customary manner, i. e. by means of a flushing system or by burning. A further object of this invention is the provision of a menstrual pad comprising such wrapper which minimises excoriation.

With these and similar objects in view, this invention comprises a wrapper comprising a sheet of gauze to which a smaller and substantially rectangular sheet of thin liquid-impervious and flexible skin material presenting an unbroken surface wide enough to provide an adequate covering for the body part to which the wrapper is to be applied is permanently secured; said smaller sheet being positioned entirely upon said gauze sheet and being secured to said gauze sheet along two opposite edges of said smaller sheet; a central portion of said smaller sheet of substantial width being free to move relatively to said gauze sheet.

By an adequate covering is meant adequate to cover the body part despite the normal movements of the wearer. That is to say, the part will remain covered despite such relative movement of the part and the wrapper as may normally occur while the wrapper is in use.

This invention also comprises a wrapper comprising a strip of gauze and a strip of thin liquid-impervious and flexible skin material; said skin strip being, in the direction of said edges, shorter than said gauze strip and having a width which is preferably less than half the width of said gauze strip but enough to provide an adequate covering for the body part to which the wrapper is to be applied; said skin strip being positioned entirely upon said gauze strip and so that the width of the uncovered portion of the gauze strip at one side of the skin strip is at least equal to the width of the skin strip; said skin strip being secured to said gauze strip along two opposite folded-over edges of said skin strip, leaving the skin material between said two edges free for movement relatively to the gauze material facing said skin material.

2

This invention also comprises a menstrual pad comprising an absorbent wad of cotton wool inserted in a wrapper as specified in either of the two last preceding paragraphs.

This invention further comprises features and combinations of features which will be apparent from the following description and the accompanying drawings in which:

Figure 1 illustrates a wrapper.

Figure 2 is a perspective view of a menstrual pad comprising the wrapper shown in Figure 1.

Figure 3 is an enlarged cross-section on 3—3 of Figure 2.

With reference to Figure 1, 2 indicates a sheet 15 strip of gauze to which is secured a skin 3 of liquid impervious highly flexible and smooth material of film-thickness.

The skin 3 is of smaller area than the gauze sheet 2; and a preferred manner of attaching it 20 to the gauze is indicated in Figure 1 which shows the edges 4 of the skin 3 turned over; and the faces 5 of said turned over edges cemented to the gauze sheet 2. This ensures that the smoothness of the outer surface 6 of the skin 3 is not impaired which is important for the wearer's comfort. The term "material of film-thickness" is intended to mean that the thickness of the material is so small and its flexibility is so great that a skin made of such material is incapable of maintaining the form given to it by a wad, without the support of the wad. Rubber of film-thickness such as may be produced by once dipping a former in latex is smooth and soft and is suitable as the skin material.

When the wrapper is to be used with a menstrual pad, it is desirable that the gauze wrapping shall be on the one hand strongly adherent to the absorbent wad of such pad to stabilize the latter and on the other hand readily unfoldable therefrom without appearing outside the skin; and for this purpose it is necessary that the last wrapped edge of the gauze sheet shall appear at the catchment surface of the assembled pad, in order that the unwrapping may be commenced 45 by lifting this edge away from the cotton wool. To accomplish this whilst having substantially more than a single layer wrapping, the sheet 3 of skin material is positioned eccentrically on the gauze sheet 2 and so as to leave at one side of it a free gauze flap 7 of less extent than the width of the wad and a considerably wider similar flap 8 at the other side.

A menstrual pad comprising a wrapper of this kind is illustrated in Figures 2 and 3. As shown 55 in these figures, the pad comprises an absorbent wad 9 of thick cellulose wadding, such as cotton wool, lightly compressed, around which is wrapped the wrapper 2, 3 so that the gauze sheet 2 encloses and confines the wad 9. In the cross-section of 60 the assembled pad the skin 3 covers the base 10 and sides 11, 11 of the wad and leaves the upper

surface 12 thereof exposed to act as a catchment surface.

In assembling the pad, the wrapping of the composite gauze and skin sheet about the wad is commenced with the application of the edge 13 of the wider flap 3 to the wad at such point 14, Figure 3, of the circumference of the latter that, as the wrapping proceeds in say the clockwise direction shown, the edges 15, 16 of the skin register successively with the upper edges of the wad, and finally the edge 17 of the gauze appears over the catchment surface and above the gauze layer already lying on said surface. The disassembling of the pad after use is commenced by picking up said gauze edge 17 and the unwrapping proceeds 15 anti-clockwise.

The pad may be formed in the customary manner with means for attaching it to a belt or other supporting means. For example, the gauze sheet 2 may be made sufficiently long to provide, at both ends of the wad, loose ends 18, 19 which may be tied into knots.

The container capacity of the skin 3 when distended by the wad, ensures that no leakage from the pad occurs even in the event of the central area of the absorbent material becoming saturated.

In a modification of the example of Figures 2 and 3, a wrapper of the kind shown in Figure 1 is wrapped around the central portion of a pad which comprises a wad and a first gauze wrapper providing the aforementioned loose ends 18, 19. In this case, the length of the gauze sheet 2 is preferably made substantially equal to the length of the wad so that the wrapper does not extend beyond the ends of said wad. The position and shape of the skin is in this case materially the same as in the pad of Figures 2 and 3; and the wrapper may be applied to the pad by the same procedure as has been described with reference to Figure 3.

In a process suitable for the manufacture of wrappers on a mass-production scale, a strip of gauze of suitable width and of indefinite length is fed onto a table and has two parallel lines of suitable adhesive imprinted thereon at suitable intervals. Skin strips are placed onto the adhesive-imprinted gauze to be secured to the latter by the adhesive; and the gauze strip is thereupon cut into pieces of suitable length, each of which has a skin strip attached thereto in the prescribed position.

I claim:

1. As a new article of manufacture, a wrapper comprising a strip of gauze and a substantially rectangular strip of thin liquid impervious and flexible skin material; said skin strip being shorter and narrower than said gauze strip but wide enough to provide an adequate covering for the body part to which the wrapper is to be applied, and being positioned entirely upon said gauze strip and so that the uncovered part of the gauze strip at the one side of said skin strip is substantially wider than the uncovered side of the gauze strip at the opposite side of said skin strip; said skin strip being secured to said gauze strip along two opposite folded-over edges of said skin strip leaving the skin material between said two edges free for movement relatively to the gauze material facing said skin material and the combined widths of the said uncovered sides of the gauze strip being greater than the width of said skin strip.

2. As a new article of manufacture, a wrapper

comprising a strip of gauze and a strip of thin liquid impervious and flexible skin material; said skin strip being shorter than said gauze strip and having a width which is less than half the width of said gauze strip but is wide enough to provide an adequate covering for the body part to which the wrapper is to be applied, said skin strip being positioned entirely upon said gauze strip and so that the width of the uncovered portion of the gauze strip at one side of the skin strip is greater than the width of the skin strip; said skin strip being secured to said gauze strip along two opposite folded-over edges of said skin strip, leaving the skin material between said two edges free for movement relatively to the gauze material facing said skin material.

3. A menstrual single-use pad comprising a wad of absorbent material and a wrapper as claimed in claim 1 loosely wrapped around said wad; the skin sheet of said wrapper extending unbrokenly over the bottom of said pad so as to render said bottom fluid-tight in at least the central portion of the length of said pad, the portion of the skin sheet extending over the bottom of the pad being free to move relatively to the gauze sheet.

4. A menstrual single-use pad comprising a wad of absorbent material and a wrapper as claimed in claim 1 loosely wrapped around said wad; the skin sheet of said wrapper extending unbrokenly over the bottom and the sides of said pad so as to render said bottom and said sides fluid-tight in at least the central portion of the length of said pad, the portion of the skin sheet extending over the bottom of the pad being free to move relatively to the gauze sheet.

5. A menstrual single-use pad comprising a wad of absorbent material; and a wrapper consisting of a sheet of gauze and a substantially rectangular smaller sheet of liquid-impervious and flexible skin material presenting an unbroken surface, positioned entirely upon said gauze sheet and so secured thereto along two opposite lateral edges of the skin sheet that the central portion of the skin sheet is free to move relatively to the gauze sheet; the wrapper being loosely wrapped around the absorbent wad with the skin sheet extending unbrokenly over the bottom and the sides of the wad so as to render the bottom and sides fluid-tight in at least the central portion of the length of the pad.

6. The pad claimed in claim 5 in which opposite edges of the skin sheet are inwardly folded back over the skin sheet and in which the skin sheet is secured to the gauze sheet by adhesive along the folded back edges of the skin sheet.
